UNITED STATES PATENT OFFICE.

JOHN B. SUMNER AND RICHARD W. HICKING, OF WORCESTER, MASSACHUSETTS.

FLYING-MACHINE.

1,292,662.

Specification of Letters Patent. Patented Jan. 28, 1919.

Application filed March 13, 1918. Serial No. 222,179.

To all whom it may concern:

Be it known that we, JOHN B. SUMNER and RICHARD W. HICKING, citizens of the United States, residing at Worcester, in the county of Worcester and State of Massachusetts, have invented certain new and useful Improvements in Flying-Machines, of which the following is a specification.

This invention relates to a flying machine of the heavier-than-air type built on the parachute principle.

A particular object of the invention is to provide means associated with the parachute employed which is operable to increase or diminish the air-resisting surface as desired and to preferably employ such means in the form of independently operable auxiliary planes having control means for their operation disposed adjacent the aeronaut's seat.

A further desideratum is to provide a generally improved construction, specifically improved in the particulars which will be hereinafter pointed out in connection with accompanying drawings illustrating one preferred embodiment, and wherein:—

Figure 1 is a side elevation partly broken away, of a flying machine constructed in accordance with my invention;

Fig. 2 is a cross sectional view on the line 2—2 of Fig. 1, and

Fig. 3 is a cross sectional view on the line 3—3 of Fig. 1.

Referring specifically to the drawings, a top of umbrella or parachute form is provided at 5 which has a plurality of independent segmental auxiliary planes 6 secured to and extending outwardly from its edge. The parachute and planes may be made of any desired material, for instance, canvas or other cloth, and be reinforced by aluminum, other metallic or wooden stays. Hinges 7 secure the auxiliary planes to the parachute and the pintles of the hinges of each auxiliary plane aline so that the auxiliary planes may swing.

Depending from the parachute and fastened thereto as a suitable number of struts 8 of wood, light metal or other suitable material. Four of these struts may be employed as shown in the drawings and be disposed to taper inwardly as shown in Fig. 1, at their bases where they are suitably secured to a platform 9. The operator's seat 10 is supported from this platform.

A shelf 11 is suitably secured to the struts

and it serves as the support for an engine 12 which drives a propeller 13, keyed to its main shaft, in a horizontal plane. Said shaft extends through and below the shelf and is there provided with a bevel gear 60 wheel 14 which meshes with a bevel gear wheel 15. The gear wheel 15 is keyed to a shaft 16 mounted horizontally in bearings 17 depending from shelf 11. A propeller 18 is fastened to shaft 16 and rotates in a vertical 65 plane.

At 19, a rudder is provided which swings horizontally and is operated in any convenient manner in the well known way which is unnecessary to here set forth as it forms no 70 part of the invention. The control or operating means of the engine also has not shown as any suitable type may be used, and the specific type is not within the province of this invention.

Planes 6 are operated in a suitable manner, preferably by a means operable from the seat 10. To this end, bars 19' are fastened to the auxiliary planes, which have an eyelet 20 at each end. Cords 21 have their terminals fastened to the eyelets and the cords in some instances passing over guide pulleys 21^a on the struts and all over suitable drums or pulleys 22 keyed to shafts 23 and journaled in brackets 24 fastened to the 85 struts. Levers 25 are fixed to shafts 23 and extend on opposite sides of and adjacent the operator's seat.

In operation, through power derived from the engine, propeller 13 lifts or elevates the 90 machine while the propeller 18 drives it forward. As the machine ascends, the parachute 5 in effect, "climbs" the air and the planes 6 may be extended to add to the air resisting surface of the parachute. These 95 planes may also be adjusted inwardly during descending so as to offer less resistance to the air. These planes 6 are shifted through operation of the levers 25 which turn the drums 22, shift the cords 21 and 100 accordingly vary the angle of the auxiliary planes. It will be noted that these planes are adjustable independently. This is advisable as it may become necessary during flight to "right" the machine. The rudder 105 is operated in any suitable manner for steering purposes in the usual way.

Since merely the preferred embodiment of the invention has been illustrated and described it is to be understood that changes in 110

the details of construction may be resorted to within the spirit and scope of the invention as defined by appended claims.

We claim:—

- 5 1. In a flying machine, a parachute, struts rigid with and depending from the parachute, propeller means mounted from the struts, a prime mover, auxiliary planes without the parachute and frame, said auxiliary planes being pivoted to the parachute substantially at its marginal edge, and means connected to the auxiliary planes and to the struts operable to vary the positions of the auxiliary planes.
- 10 2. In a flying machine, a parachute, struts depending therefrom, a platform secured to said struts, a seat on said platform, a shelf secured to said struts, a plurality of auxiliary planes pivoted adjacent the edge of the parachute, flexible members having their ter-
- 15 minals spaced apart and secured to the auxiliary planes, brackets secured to the struts, drums mounted in said brackets, levers to turn said drums disposed adjacent the seat, a prime mover mounted on said shelf, a 25 horizontally movable propeller driven by said prime mover, the main shaft of the engine extending through the shelf, bearings depending from the shelf, a shaft journaled in said bearings, gearing to drive said shaft 30 from the main shaft, and a propeller fastened to the second mentioned shaft operable in a vertical plane.

In testimony whereof we affix our signatures in presence of two witnesses.

JOHN B. SUMNER.

RICHARD W. HICKING.
